INVENTOR
NELS ANDERSON

BY
Milton S. Crandall,
ATTORNEY

UNITED STATES PATENT OFFICE.

NELS ANDERSON, OF HURLEY, SOUTH DAKOTA.

NUT-LOCK.

1,086,342.

Specification of Letters Patent.

Patented Feb. 10, 1914.

Application filed July 5, 1913. Serial No. 777,468.

To all whom it may concern:

Be it known that I, NELS ANDERSON, a citizen of the United States, and a resident of Hurley, in the county of Turner and

5 State of South Dakota, have invented certain new and useful Improvements in Nut-Locks, of which the following is a specification.

This invention relates to nut-locks, and 10 has for its object the construction of a device of this class inexpensive in manufacture yet thoroughly reliable in operation.

Another object of the invention is the provision of integral locking means which does 15 not protrude from the bolt and has no removable key or other parts.

With these and other objects in view, the invention will be fully understood from the following description, reference being had 20 to the accompanying drawings forming a part of this application and in which like characters of reference indicate corresponding parts throughout the several views, of which,—

25 Figure 1 is a plan view of a nut constructed in accordance with my invention; Fig. 2 is a side elevation of the same; Fig. 3 is a vertical section of the same, taken on the line 3—3 of Fig. 1, and locked upon a bolt; 30 Fig. 4 is an enlarged perspective view of the bolt-engaging key.

The invention consists of a nut provided with an angled groove in one face thereof; and an angled key journaled within said 35 groove; armed with bolt-engaging means and normally secured by spring engagement of the key within the groove, all of which will presently be made more clear.

Referring, now, to the illustrations, 5 is a 40 nut, of any suitable shape, provided with an angled groove, as that formed by the intersecting grooves, 6 and 7, the former of which communicates with the threaded opening of the nut. The key I prefer to employ comprises the cylindrical member, 8; the handle, 9, formed integrally therewith and disposed at an angle thereto; and a lug portion, 10, carried by the member, 8. The key portion, 8, is free to turn within the

groove, 6, and is secured therein in any 50 suitable manner, preferably by crimping the edges of the groove over the key, as clearly indicated at 11.

Prior to turning or unturning the nut upon a bolt, the key is turned into the position indicated by the dotted lines in Fig. 1, and when in such position, the cam, or eccentric, 10, will lie outwardly from the bolt and within a notch, 12 in the nut provided to admit it. When the nut is turned to the desired point, the key is turned inwardly and the arm, or handle, 9, sprung into the groove, 7, by virtue of which, displacement of the handle is prevented and the cam securely impressed into the threaded portion 60 of the bolt. The nut is readily unlocked by inserting a pointed instrument at the point, 13, between the end of the handle and the bottom of the groove, 7.

Where nuts are not turned into engagement with seats, as is the case with vehicle-axle burs, etc., the bolt, or externally-threaded members, may be provided with longitudinal slots, as at 14, Fig. 3, adapted to receive the cam. By virtue of this arrangement the threads are not mutilated by engagement of the cam.

Having thus described my invention, what I claim as new and desire to secure by Letters Patent, is,—

1. An article of the class described comprising a nut having two converging grooves in one face thereof, disposed at an angle each to the other, and one of said grooves communicating laterally with the threaded opening 85 of the nut; an angled key, one portion of which is rotatably-secured within the latter groove and the other portion adapted to be sprung into the other groove; and bolt-engaging means on the rotatable portion of the 90 key.

2. The combination with a longitudinally-slotted bolt, of a nut having two grooves in one face thereof, each intersecting the other, and one of said grooves communicating 95 laterally with the threaded opening of the nut; a key mounted to turn within the latter groove; a lug carried by said key and adapt-

ed to engage the slotted portion of the bolt when the key is turned in one direction and disengaged from said slotted portion when turned in the opposite direction; and a handle secured at an angle to said key and adapted to be normally-secured within the other groove.

In testimony whereof I have hereunto set my hand, this 28 day of June, in the presence of two witnesses.

NELS ANDERSON.
